Filed May 21, 1962, Ser. No. 70,208

Term of patent 14 years

(Cl. D50—6)

FIG. 1.

FIG. 2.

FIG. 1 is a perspective view of a combined furniture handle and escutcheon therefor, showing my new design.

FIG. 2 is a rear perspective view thereof.

The characteristic feature of my design resides in the escutcheon in combination with conventional knob as shown.

I claim:

The ornamental design for a combined furniture handle and escutcheon therefor, as shown and described.
